UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed September 26, 1930. Serial No. 484,512.

This invention relates to car roofs of the riveted up type wherein the roof sheets span from side plate to side plate. The invention is especially applicable to that type of roof

5 wherein the body portions of the roof sheets form panels at one level alternating and connected with panels at a lower level. In this type of roof, which is more fully set forth in Bonsall Patent No. 1,526,768 granted February 17, 1925, the sheets constitute load supporting members which function after the manner of a beam and make it practicable to wholly dispense with carlines. The principal object of the present invention is to devise 10 a seam construction for this type of roof which will aid in taking care of stresses in the roof, be safer against leakage and permit sheets of different thicknesses to be used at different levels, and to decrease the weight of 15 the roof and increase the strength thereof.

The invention consists principally in the seam construction and in the arrangement and combination of parts hereinafter described and claimed.

20 In the accompanying drawings, which form part of this specification and wherein like numerals refer to like parts wherever they occur,

Fig. 1 is a top plan view of a portion of 25 a car roof embodying my invention,

Fig. 2 is an enlarged vertical transverse cross-section through one-half of the roof on the line 2—2 in Fig. 1,

Fig. 3 is a vertical transverse cross section 30 on the line 3—3 in Fig. 1,

Fig. 4 is a longitudinal cross section on the line 4—4 in Fig. 1,

Fig. 5 is an enlarged vertical cross section 35 through one of the seams at the ridge, on the line 5—5 of Fig. 2,

Figs. 6 and 7 are longitudinal cross sections similar to Fig. 4, showing roof sheets of modified form,

Fig. 8 is a vertical cross section through the 40 roof at the eaves, showing a modified arrangement for supporting the roof sheets from the side plate,

Fig. 9 is a vertical cross section on the line 45 9—9 in Fig. 8; and

Fig. 10 is a cross section through the joint

between the upper and lower panels of adjacent sheets, showing a seam cap whose upper portion is thicker than the lower portion thereof.

According to the present invention, the roof comprises sheets 1, 2, which are pitched or arched and span from side plate to side plate and have their ends preferably turned down and riveted or otherwise secured to the side plates 3; and the sides of each sheet 55 are provided with upstanding flanges 4, 5. The upstanding flanges of adjacent sheets abut flatwise and are secured together by horizontal rivets 6 above the upper level 60 of the sheets. Preferably the body of the sheet 1 on one side of the joint or seam is at a different level from that of the sheet 2 on the other side of said joint or seam; by reason of which the flange 5 of the sheet 2 at the lower level is deeper than the flange 65 of the sheet at the upper level, the portion of the deeper flange between the two levels thus serving as an offsetting web that harnesses together the panels at the different 70 levels so as to make them function after the manner of a beam.

The upstanding flanges of a seam or joint are straddled by a seam cap 7 secured thereto by the horizontal rivets 6 above mentioned, 75 which pass through the sheet flanges as well as the legs of the seam cap. The seam cap serves not only to keep moisture from entering at the joint and to protect the edges of the sheets against rusting and mechanical injury, but it adds greatly to the strength and 80 load carrying capacity of the sheets. In the design of seam cap illustrated in Fig. 5, the legs thereof are of unequal length and are bent at their lower portions to form horizontal flanges 8 immediately above the respective sheets.

Preferably the seam caps are made of plates of such thickness and folded on such longitudinal lines as to provide such amount 85 of metal and at such places as may be needed to satisfy the computations of the designer. Usually such plates are of substantially uniform width and folded along a longitudinal line far enough from the medial line thereof to produce the desired inequality of the 90

legs thereof, with each leg bent laterally on longitudinal lines that diverge upwardly from a point at the mid length thereof. The thickness of such seam covers may be 5 uniform or not. It is an important advantage of the seam cap that it reinforces the vertical flanges or web portions against buckling and protects them from mechanical injury and thereby contributes greatly to the 10 strength of the roof. It is a special advantage of the seam cap illustrated in Fig. 10 that it enables the metal to be concentrated as desired at the uppermost portion thereof.

The design of roof sheet admits of variation. For instance, in the construction shown 15 in Sheet 1 of the drawings, the body portion of some roof sheets is wholly at the upper level and the body portion of other roof sheets is wholly at the lower level, the sheets 20 1 at the upper level having relatively narrow flanges 4 along each side and the sheets 2 at the lower level having relatively deep flanges 5 along each side. In the construction of Fig. 7, each sheet is offset along a 25 longitudinal line 9 near the medial line thereof so that one-half of the body portion constitutes a panel 10 at the upper level and is provided with a narrow side flange 11 while the other half of the body portion 30 constitutes a separate panel 12 at the lower level and is provided with a wide side flange 13. Sheets of both of these simple designs are easy to make without injuring the metal or the galvanizing thereof.

35 In the construction of Fig. 6, each sheet is offset along the longitudinal line 9a near the medial line thereof, in the manner shown in Fig. 7, so that one-half constitutes a panel 10a at the upper level and the other half 40 constitutes a panel 12a at the lower level; and both panels are provided with relatively narrow side flanges 11a of the same depth. The sheets are arranged on the car by turning every other sheet end for end so that the 45 high panels of the sheets are adjacent to each other and the low panels are also adjacent to each other. The upstanding side flanges 11a of adjacent panels abut flatwise and are straddled by inverted U-shaped seam caps 7a 50 secured thereto by horizontal rivets 6a, which pass through the side walls of said seam caps and the abutting flanges straddled thereby. The side walls of the seam caps are bent outwardly at their lower edges to form out- 55 standing base flanges 8a that bear flatwise against the panels of adjacent sheets. By this arrangement, the high and low panels of adjacent sheets cooperate with each other to form alternating hollow ribs and chan- 60 nels, respectively; and the seam caps, which are symmetrical by reason of the sheets being joined at the same level, are disposed alternately at upper and lower levels.

65 Figs. 8 and 9 illustrate a modified construction for supporting the roof sheets at the

eaves' ends of the transverse roof joints. Said construction comprises an angular flashing member 14 which is located beneath the corners of adjacent sheets and extends a short distance on each side of the joint between said sheets. The vertical flange of this angle is located between the down-turned eaves' ends of the sheets and the upstanding innermost flange of the Z-bar side plate 3 and is secured to said side plate flange by 70 the rivets which secure the eaves' ends of the sheets thereto. The other flange of the angle sheet supporting bracket projects inwardly over the upper edge of the upstanding innermost flange of the Z-bar side plate beneath 75 the body portions of adjacent sheets to form a support therefor. As shown in the drawings the inwardly extending flange of the sheet supporting bracket is offset vertically on opposite sides of the roof joint located 80 thereabove so that the portion 15 of said flange at the lower level serves as a support for the low panel of one sheet and the portion 16 of said flange at the high level serves as a support for the high panel of the other 85 sheet. The panels, together with the base flanges of the seam cap resting thereon, are secured to the vertically offset portions of the sheet supporting flange of the bracket 90 14 preferably by means of vertical rivets 17. 95

Fig. 10 represents a modified form of seam cap 7b, wherein the lower portions of said seam cap below the rivets are made thinner than the upper portion of the cap. With this construction, a considerable amount of 100 metal is massed at the top of the cap where it is more efficient in action.

The construction hereinbefore described combines the advantages of a solid riveted up roof having external carlines with the 105 advantages of a roof made without carlines by arranging the body portions of the sheets at different alternating high and low levels. Thus, for equal strength, the new construction may be made of lighter sheets; especially 110 the sheets of the upper level may be made lighter by reason of the special cooperation therewith of the seam cover in relieving them of a considerable part of that duty. Likewise, as the rivets are wholly outside of the 115 roof covering, the seams afford better protection against the weather than seams that have the rivets entering the car.

What I claim is:

1. A car roof comprising roof sheets adapted, arranged and secured together at their side margins by upstanding seams to constitute panels at one level alternating with panels at a different level, the edges of adjacent panels being connected by vertically disposed 120 web portions, the side margins of adjacent sheets having upstanding flanges that abut and seam caps that straddle adjacent up- 125 standing flanges and are rigidly secured thereto.

2. A car roof comprising roof sheets offset along longitudinal lines to form panels at different levels and provided with upstanding flanges along their sides, said sheets being arranged so that a low panel of one sheet is adjacent to a high panel of the next sheet, and seam caps which straddle the adjacent flanges of adjacent sheets and are rigidly secured thereto. 70
- 10 3. A car roof comprising roof sheets offset along longitudinal lines to form panels at different levels and provided with upstanding flanges along their sides, said sheets being arranged so that a low panel of one sheet is adjacent to a high panel of the next sheet, and seam caps which straddle the adjacent flanges of adjacent sheets and are rigidly secured thereto, said seam caps having lateral flanges disposed immediately above the adjacent panels respectively. 75
- 15 4. A car roof comprising roof sheets adapted, arranged and secured together at their side margins by upstanding seams to constitute panels at one level alternating with panels at different levels, the edges of adjacent panels being connected by vertically disposed web portions and the side margins of adjacent sheets having upstanding flanges that abut, and a seam cover straddling said flanges and secured together therewith by rivets above the upper level, the upper portion of said seam cover being thicker than the lower portion thereof. 80
- 20 5. A car roof comprising roof sheets whose adjacent marginal portions are at different levels and provided with upstanding flanges that abut flatwise and seam covers straddling said flanges and secured thereto, said seam covers each comprising a plate folded on itself along a longitudinal line spaced from the medial line thereof to form side walls of unequal height, said side walls having alined rivet holes. 85
- 25 6. A car roof comprising roof sheets whose adjacent marginal portions are at different levels and provided with upstanding flanges that abut flatwise and seam covers straddling said flanges and secured thereto, said seam covers each comprising a plate folded on itself along a longitudinal line spaced from the medial line thereof to form side walls of unequal height and having outturned lateral flanges at the bottom of said walls. 90
- 30 7. A car roof comprising roof sheets whose adjacent marginal portions are at different levels and provided with upstanding flanges that abut flatwise and seam covers straddling said flanges and secured thereto, said seam covers each comprising a plate of uneven thickness folded on itself along a longitudinal line spaced from the medial line thereof to form side walls of unequal height, the upper portion of said cover being of greater thickness than the lower part thereof. 95
- 35 8. A car roof comprising roof sheets whose adjacent marginal portions are at different levels and provided with upstanding flanges that abut flatwise and seam covers straddling said flanges and secured thereto, said seam covers each comprising a plate folded on itself along a longitudinal line spaced from the medial line thereof to form side walls of unequal height, said side walls having alined rivet holes and having outturned flanges at the bottom. 100
- 40 9. A car roof comprising roof sheets extending from side plate to side plate with their adjacent margins at different levels and a member attached to the side plates and having sheet supporting portions located between the margins of adjacent sheets at the level of each margin. 105
- 45 10. A car roof sheet whose body comprises longitudinally extending portions arranged at different levels, said sheet having a relatively shallow flange along the side margin of the upper level and a relatively deep flange along the side margin of the lower level. 110
- 50 11. A car roof comprising roof sheets extending from side plate to side plate with the adjacent corners of adjacent sheets at different levels, and sheet supporting members secured to the said plates below the corners of the sheets, such members each having a flange at its top that is offset vertically to provide an upper seat for the corner of one sheet and a lower seat for the corner of the adjacent sheet. 115
- 55 12. A car roof whose longitudinal cross section comprises raised panels at one elevation alternating with depressed channels at a lower elevation, said roof consisting of roof sheets which have upstanding flanges at their side margins, said flanges being covered with seam caps, said seam caps and said flanges being rigidly secured together. 120
- 60 13. A car roof of the kind wherein the roof sheets are adapted, arranged and secured together at their side margins by upstanding seams to constitute panels at one level alternating with panels at a different level, said roof comprising a series of spaced roof sheets arranged at one level and forming the upper panels of the roof and another series of spaced roof sheets arranged at a lower level and forming the lower panels of the roof and staggered with relation to the sheets of the upper level, the sheets of both series having upstanding side flanges that extend above the upper level and are rigidly secured together. 125
- 65 14. A car roof of the kind wherein the roof sheets are adapted, arranged and secured together at their side margins by upstanding seams to constitute panels at one level alternating with panels at a different level, said roof comprising a series of spaced roof sheets at one level and forming the upper panels of the roof and a series of spaced roof sheets at a lower level and forming the lower panels of the roof and staggered with relation to the 130

sheets of the first series, all of said sheets having upstanding flanges at the sides, and seam caps that straddle adjacent flanges of adjacent sheets and rivets extending horizontally through said seam caps and flanges.

5 15. A car roof having alternating ribs and channels extending crosswise of the car, said roof consisting of load sustaining sheets that are connected together by seams located at the tops of the ribs and intermediate the side walls of the channels.

10 16. A car roof having alternating ribs and channels extending crosswise of the car, said roof consisting of roof sheets that are connected together by seams located alternately at upper and lower levels.

15 Signed at New Kensington, Pennsylvania,
this 22nd day of Sept. 1930.
